US0D1112599S

(12) **United States Design Patent** (10) **Patent No.:** **US D1,112,599 S**
(45) **Date of Patent:** **** Feb. 10, 2026**

(54) **WATER TOWER TREATMENT SYSTEM**

(71) Applicant: **H2o Concepts International Inc.**,
Phoenix, AZ (US)

(72) Inventor: **Sven Mierswa**, San Carlos (MX)

(73) Assignee: **H2O CONCEPTS
INTERNATIONAL, INC.**, Phoenix,
AZ (US)

(**) Term: **15 Years**

(21) Appl. No.: **29/937,718**

(22) Filed: **Apr. 16, 2024**

(51) LOC (15) Cl. **23-01**

(52) U.S. Cl.

USPC **D23/207**

(57) **CLAIM**

The ornamental design for water tower treatment system as shown and described.

DESCRIPTION

FIG. 1 illustrates a top perspective view of an embodiment of the water tower treatment system;

FIG. 2 illustrates a right side view thereof;

FIG. 3 illustrates a left side view thereof;

FIG. 4 illustrates a front plan view thereof;

FIG. 5 illustrates a back plan view thereof;

FIG. 6 illustrates a top plan view thereof; and,

FIG. 7 illustrates a bottom plan view thereof.

The water tower treatment system has been shown with break lines in its height. The appearance of any portion of the article between the break lines forms no part of the claimed design.

1 Claim, 4 Drawing Sheets
